UNITED STATES PATENT OFFICE.

SAMUEL LINDON MARPLE, OF CLAIRTON, PENNSYLVANIA.

STEAM-BOILER.

SPECIFICATION forming part of Letters Patent No. 748,765, dated January 5, 1904.

Application filed May 26, 1903. Serial No. 158,841. (No model.)

To all whom it may concern:

Be it known that I, SAMUEL LINDON MARPLE, a citizen of the United States, residing at Clairton, in the county of Allegheny and State of Pennsylvania, have invented a new and useful Improvement in Steam-Boilers, of which the following is a specification.

My invention relates to improvements in the construction of a steam-boiler, and has for its object the rapid generation of steam, economy of fuel, and safety from total destruction in case of collapse or explosion.

With these objects in view the invention consists in certain novel features of construction hereinafter described and claimed, and shown in the accompanying drawings, in which—

Figure 1 is a side elevation of the boiler. Fig. 2 is a top plan view thereof. Fig. 3 is an inner end view of one of the headers, the drums and tubes being removed. Fig. 4 is a similar view of the outer end of the header.

Referring specifically to the drawings, *a* indicates a horizontally-disposed steam and water drum, having a similar drum *b* on each side thereof. Both ends of the drums communicate with headers *c*, which extend below the drums, as at *d*. A mud-drum *e* is located below the drums *a* and *b* and is connected to the headers by a series of water-tubes *f*, extending therefrom to the headers below the drums *a* and *b*. The tubes slant downwardly toward the mud-drum, which fa-

cilitates the circulation of the water. The mud-drum and headers have manholes *g* for 35 the purpose of inspection and cleaning.

Steam is taken from the drums *a* and *b* by pipes *h*, entering the same at the top. The drums *b* are smaller than the drum *a*, a good design being to make their diameter about 40 two-thirds as large as the diameter of the drum *a*.

The construction described herein gives the boiler a great heating-surface, which makes it a rapid steam-generator. It is also economical in the consumption of fuel, its resistance to rupture is great, and it is not liable to total destruction in case of collapse or explosion.

What I claim as my invention, and desire 50 to secure by Letters Patent, is—

A boiler comprising a horizontally-disposed drum, a similar drum of lesser area on each side thereof, a header on each end of the drums communicating therewith, a mud-drum 55 between the headers, and tubes extending upwardly from the mud-drum to each header, substantially as described.

In testimony whereof I have signed my name to this specification in the presence of 60 two subscribing witnesses.

SAMUEL LINDON MARPLE.
